UNITED STATES PATENT OFFICE

ALBIN P. LOFSTRAND, OF CHICAGO, ILLINOIS

RAILROAD SWITCH

Application filed April 28, 1930. Serial No. 448,036.

- This invention relates to a railroad switch and has for its primary object to provide, in a manner as hereinafter set forth, a railroad switch in which the switch points are arranged in a manner to prevent accumulation of snow between the points and the track rails with which the points are associated, and in which the mechanism for operating the switch points to open and close the same may be properly housed to protect such mechanism from snow and the like, thereby eliminating the possibility of the switch being rendered inoperative by the melting and subsequent freezing of snow.
- 15 A further object of the invention is to provide, in a manner as hereinafter set forth, a switch possessing the foregoing advantages in which the switch points are moved vertically to open and closed positions.
- 20 With the foregoing and other objects in view, the invention consists of the novel construction, combination and arrangement of parts as hereinafter more particularly described, and as illustrated in the accompanying drawing, wherein is shown an embodiment of the invention, but it is to be understood that the description and drawing are to be taken as illustrative and that the invention is intended to be limited only by the 25 scope of the claims hereunto appended.
- In the accompanying drawing in which like numerals are employed to designate like parts throughout the several views:
- Figure 1 is a sectional plan illustrating a switch in accordance with this invention.
- 25 Figure 2 is a section taken on the line 2-2 of Figure 1.
- Figure 3 is a section taken on the line 3-3 of Figure 1.
- Figure 4 is a sectional elevation showing one of the switch points in closed position.
- Figure 5 is a perspective view of one of the cam elements which supports the switch points.
- 30 Referring to the drawing in detail, the numerals 1 and 2 represent the rails of the main track of a railroad, the rail 2 having an angularly extending portion 3 forming one rail of a siding. Disposed in parallel relation to the portion 3 is a rail 4 which comprises the other rail of the siding, and disposed in parallel relation to the rail 1 is a rail 5 which comprises one rail of a continuation of the main track. The rails are supported in the usual manner on a plurality of ties as indicated at 6. Pivotaly connected to the rails 4 and 5 are a pair of switch points 7 and 8 respectively adapted for engagement with the rails 1 and 2. Each of the switch points is pivotally connected adjacent one end to a rail to permit the switch point to swing in a vertical arc. The switch points gradually decrease in height toward the free ends thereof and their outer side faces are bevelled adjacent the free ends as indicated at 9.
- 35 Seated on certain of the ties 6 and extending transversely of the track beneath the rails is a base plate 10 which forms the bottom wall of a plurality of housings 11, 12 and 13. The housing 11 is disposed outwardly of the portion 3 of the rail 2, the housing 12 is disposed between the switch points 7 and 8, and the housing 13 is disposed outwardly of the rail 1. Slidably mounted on the plate 10 is a rack bar 14 which extends transversely of the track through suitable slots formed in the rail 1 and rail portion 3. End portions of the rack bar 14 extend beneath keepers 15 mounted on the plate 10, and each end of the rack bar 14 is connected with one end of a spring 15, the opposite end of which is connected with one of the housings carried by the base plate.
- 40 In spaced relation to the ends thereof, the rack bar 14 is provided in its upper face with a series of teeth 16 and 17. Midway the ends thereof, the rack bar 14 is provided with a pin 18 which projects upwardly through an elongated slot 19 in a lever 20. One end of the lever 20 is pivotally connected to the plate 10, and the opposite end of the lever is connected with an actuating bar 21, by means of a stud 22 projecting from the bar through an elongated slot 23 in the lever. The actuating bar 21 is connected with a switch stand lever 24 disposed on one side of the track.
- 45 Disposed beneath the switch points 7 and 8 are a pair of cam elements 25 and 26. Each of the cam elements is of elongated forma-

tion, substantially elliptical in cross section, and is disposed longitudinally of a switch point. Each of the cam elements tapers from one end thereof toward the other and has its smaller end rotatably mounted within a socket 27 formed in a switch point adjacent the pivoted end thereof. The larger end of the cam element is disposed in spaced relation to the free end of the switch point. Spaced 10 from the large ends thereof, the cam elements 25 and 26 are provided with peripherally extending rows of inset teeth 28 and 29 respectively which are in mesh with the teeth 17 and 16 of the rack bar 14. The portions of the 15 cam elements 25 and 26 between the teeth 28 and 29 and the large ends of the cam elements, are seated on an extension 30 of the base plate 10. Portions of the cam elements 25 and 26, adjacent the large ends thereof, 20 are rotatably disposed within recesses 31 formed in the lower faces of the switch points 7 and 8.

Connected with the switch points 7 and 8, adjacent the free ends thereof, are a pair of 25 arms 32 which extend downwardly through slots 33 through the extension 30 of the base plate 10. The arms 32 are pivotally connected at their lower ends with the ends of a lever 34 which is disposed between a pair 30 of the ties 6, and which is pivotally mounted intermediate its ends on a rod 35 extending between the ties. The extension 30 of the plate 10 provides a cover for the lever 34 and rod 35.

35 Depending from the ends of the base plate 10 and extension 30 are aprons 36 which close the spaces between the ends of the ties upon which the plate 10 and extension 30 are mounted.

40 In the operation of the switch, the switch stand lever 24 is actuated to move the rack bar 14 transversely of the track. Upon such movement of the rack bar, the teeth 16 and 17 thereof respectively engage the teeth 29 and 28 of the cam elements 26 and 25 whereby the latter are rotated beneath the switch points 8 and 7. The cam elements 25 and 26 are so disposed with respect to each other that when the major axis of one of the cam 45 elements is disposed horizontally, the major axis of the other cam element will be disposed vertically. In Figure 2 the cam element 25 is shown with its major axis disposed vertically, in which position the switch point 50 7 is elevated to bring the free end thereof in transverse alignment with the rail 1. Upon the raising of the switch point 7, the switch point 8 is lowered owing to the arms 32 which connect the switch points with the pivoted lever 34.

55 It is to be noted that the weight of the switch points is transmitted through the cam elements 25 and 26 directly to the extension 30 of the plate 10, whereby the teeth of the cam element are maintained loosely in mesh

with the teeth of the rack bar. It is to be noted further that the switch points remain in the same vertical plane in their opened and closed positions whereby the likelihood of snow or the like accumulating between the beveled faces 9 of the switch points and the rails associated with the bevelled faces is prevented. It is to be further noted that the entire operating mechanism with the exception of the conventional switch stand is protected from the weather.

70 It is thought that the many advantages of a switch in accordance with this invention will be readily apparent, and although the preferred embodiment of the invention is as 80 illustrated and described, it is to be understood that changes in the size, shape and arrangement of parts may be resorted to, so long as such changes fall within the scope of 85 the invention as defined in the appended claims.

75 What I claim is:

1. A railroad switch comprising, a pair of pivoted switch points, a cam element disposed beneath a free end portion of each switch point, each of said cam elements being of elongated, tapered formation substantially elliptical in cross section, a circumferentially extending row of teeth on each of said cam elements, and a rack bar extending transversely of the railroad for engagement with the teeth of the cam elements to selectively move the switch points into operative position.

80 2. A railroad switch comprising, a pair of pivoted switch points, a cam element disposed beneath a free end portion of each switch point, each of said cam elements being of elongated, tapered formation substantially elliptical in cross section, a circumferentially extending row of teeth on each of said cam elements, and a rack bar extending transversely of the railroad for engagement with the teeth of the cam elements to selectively move the switch points into operative position, the 85 teeth of each of said cam elements being inset from the periphery thereof.

90 3. A railroad switch comprising, a pair of pivoted switch points, a cam element disposed beneath a free end portion of each switch point, each of said cam elements being of elongated, tapered formation substantially elliptical in cross section, a circumferentially extending row of teeth on each of said cam elements, a rack bar extending transversely of the railroad for engagement with the teeth of the cam elements to selectively move the switch points into operative position, the teeth of each of said cam elements being inset from the periphery thereof, and a rigid plate upon 95 which a longitudinal portion of each of said cam elements is seated.

100 4. A railroad switch comprising, a plate extending transversely of the railroad and projecting laterally therefrom, said plate being 105

formed centrally thereof with a lateral extension, a pair of pivoted switch points, a cam element disposed beneath a free end portion of each switch point, each of said cam elements being of elongated tapered formation substantially elliptical in cross section and having its smaller end rotatably mounted in the lower face of a switch point, a circumferentially extending row of inset teeth on each cam element in spaced relation to the larger end thereof, a rack bar slidably mounted on said plate to selectively move the switch points into operative position, a pair of arms connected with the free ends of the switch points, and a lever pivotally mounted intermediate its ends and having its ends pivotally connected with said arms.

5. A railroad switch comprising a plate extending transversely of the railroad and projecting laterally therefrom, said plate being formed centrally thereof with a lateral extension, a pair of pivoted switch points, a cam element disposed beneath a free end portion of each switch point, each of said cam elements being of elongated tapered formation substantially elliptical in cross section and having its smaller end rotatably mounted in the lower face of a switch point, a circumferentially extending row of inset teeth on each cam element in spaced relation to the larger end thereof, a rack bar slidably mounted on said plate to selectively move the switch points into operative position, a pair of arms connected with the free ends of the switch points, and a lever pivotally mounted intermediate its ends and having its ends pivotally connected with said arms, the extension of said plate providing a cover for said lever, and a plurality of housings for the end portion and intermediate portion of said rack bar, said plate providing the bottom wall of each of said housings.

6. A railroad switch comprising, a pair of vertically movable switch points, a cam element disposed beneath each switch point, a circumferentially extending row of teeth on each cam element, and a rack bar extending transversely of the railroad for engagement with the teeth of the cam elements to selectively move the switch points into operative position.

7. A railroad switch comprising, a pair of vertically movable switch points, a cam element disposed beneath each switch point, a circumferentially extending row of teeth on each cam element, and a rack bar extending transversely of the railroad for engagement with the teeth of the cam elements to selectively move the switch points into operative position, the teeth of each cam element being inset from the periphery thereof.

In testimony whereof, I affix my signature hereto.

ALBIN P. LOFSTRAND.
